CLAIM

The ornamental design for a golf toy, as shown and described.

DESCRIPTION

FIG. 1 is a perspective view of a golf toy showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is another perspective view thereof, with additional components laid out to show an alternate state of use.

The broken lines depict portions of the golf toy, and additional components in FIG. 9, that form no part of the claimed design.
